DISTILLATION APPARATUS FOR TREATING
FATTY ACID CONTAINING STOCKRalph H. Potts, La Grange, Ill., assignor to Ar-
mour and Company, Chicago, Ill., a corporation
of IllinoisContinuation of application Serial No. 424,434,
December 26, 1941, which is a division of applica-
tion Serial No. 298,722, October 9, 1939. This
application February 10, 1945, Serial No. 577,246

11 Claims. (Cl. 202—154)

1

This invention relates to treating fatty acid-containing stock and the like and deals particularly with improved apparatus for conducting the improved practice. This application is a continuation of my copending application Serial No. 424,434, filed December 26, 1941, now abandoned, which is in turn a division of my copending application Serial No. 298,722, filed October 9, 1939, now matured into Patent No. 2,322,056, issued June 15, 1943.

It is now common practice to pass fatty acid-containing stock through a pipe still and thence into a fractionating tower, steam being employed in the bottom of the tower for stripping the bottoms, the steam and the uncondensed portion of the stripped vapors passing up and out of the tower. This process has several disadvantages. The volume of the steam, air and other gases introduced with the feed stock makes it difficult to maintain the desired high vacuum. Furthermore, the ascending steam and gases, by reason of molecular weight differences and through entrainment, militate against sharp separation of the fractions. The presence of air and low boiling fractions tends to produce decomposition and discoloration. The non-uniform content of moisture within the feed stock produces an additional steam load in the fractionating tower and surging due to varying amounts of moisture.

An object of the present invention is to produce a sharp separation of the fractions within the fractionating tower through the exclusion of steam and such gases, and, in general, to overcome the disadvantages above referred to. A further object is to improve yields, insure closer cut fractions of improved odor and color, prevent decomposition of the unsaturated fractions, and reduce operating costs. Another object is to provide apparatus in which the stock is first stripped or fractionated with steam and is thereafter distilled at a lower pressure. A further object is to provide apparatus in which the steam which is necessary for stripping the bottoms is substantially excluded from the fractionating tower, the same steam which is employed for stripping together with the stripped vapors being utilized for de-aerating the incoming feed stock, removing the moisture thereof, and the low boiling fraction containing odoriferous substances. A still further object is to provide apparatus in which the bottoms from the fractionating tower are withdrawn and stripped of vapors at low temperatures, the stripped vapors being returned without substantial heat loss to the fractionating tower. Other

objects and advantages will appear as the specification proceeds.

The invention is illustrated, in a preferred embodiment, by the accompanying drawing in which the single figure represents, in a diagrammatical manner one embodiment of apparatus suitable for carrying out the improved process.

The process may be described broadly, in connection with the apparatus, as follows. The feed stock containing fatty acids enters through pipe 10 into the heat exchanger, or other suitable form of heater. In the heat exchanger shown, a heating fluid such as a Dowtherm may be passed through the inlet pipe 11 and out of the exchanger through the pipe 12, the pipes leading to a suitable external heating source (not shown). From the heat exchanger, the stock flows through pipe 13 into the stripping or fractionating tower at about the middle of its top section. As the stock flows downwardly, it meets a rising column of steam and vapors from the bottom of the tower, the steam and vapors aiding in the removal of air and moisture from the feed stock. At the same time, there is removed a small fraction, about five per cent, of low boiling fatty acids and other odoriferous substances. The stripping or fractionating tower described serves the function not only of stripping vapors from the bottoms, but also of fractionating the rising column of vapors.

The steam, air and vapors thus withdrawn pass through the pipe 14 and surface condenser 15, the steam passing into the catchall through pipe 16 and the condensed fatty acid vapors passing downwardly through pipe 17 into the down tank. The steam in the catchall passes upwardly to a barometric condenser (not shown), by means of which, the pressure on the stripping tower is maintained at about 50 mm. Hg.

From the down tank, the condensate flows into a pump and about two-thirds of it is returned by the pump to the top of the stripping tower as reflux, the remaining one-third being removed as product.

The de-aerated and dried feed stock then flows by gravity through the pipe 18, which provides a seal 19, into the fractionating tower. Preferably, the top portion of the tower is maintained at a pressure of 2 mm. Hg and the pressure at the base is not greater than 32 mm. Hg. The bottom of the fractionating tower is heated by a Dowtherm Calandria type of base heater 20.

The vapors from the top of the tower pass off through pipe 21 and are condensed in the surface condenser 22. The major portion of the distillate

from the condenser 22 is returned by the pump 23 through line 24 to the top of the fractionating tower as reflux. A smaller portion passes through cooler 25 to a point of recovery.

Bottoms from the tower flow by gravity through the pipe 28, which is formed with a vertical run as shown to trap vapors and to permit a pressure differential thereacross, into the flash drum or chamber where the vapors, after passing through the entrainment eliminators 27, pass through pipe 28 and are condensed in the surface condenser 29. The condensers 22 and 29 are connected by a manifold pipe 30 and a vacuum is maintained therein through the use of vacuum pumps and barometric condensers of well-known structure.

The flash drum is provided with a heating coil 31 connected with the Dowtherm pipes, suitable valves being placed in the lines permitting the coil to be used when desired. In ordinary practice, it is found unnecessary to heat the bottoms within the flash drum. The bottoms from the flash drum are withdrawn through pipe 32 and pumped through pipe 33 to a lower portion of the stripping tower. As the bottoms flow downwardly over the trays in the tower, they meet the ascending steam which strips the bottoms. The unvaporized portion of the bottoms is withdrawn through pipe 34 and passed through a cooler 35 to a point of recovery.

It will be noticed that the Dowtherm vapor or other suitable heating fluid is circulated through pipes 36 and 37 and through valve controlled pipes leading into the base heater 20 and the coil 31, the valves permitting the application of heat to be accurately controlled in the fractionating tower and in the flash drum.

The distillate which is recovered from the flash drum condenser 29 passes downwardly through pipe 38 and is then pumped through line 39 and cooler 40 to a point of recovery.

Specific operation

In order to illustrate the operation of the method, a specific example may be given as follows.

Five thousand pounds per hour of acidulated cotton seed foots containing from 80 per cent to 85 per cent of free fatty acids (150° F.), enters the heat exchanger through the pipe 10 and is brought up to a temperature of 450° F. within the heat exchanger or heater. The stock enters the stripping tower and passes down over a series of stripping trays where it is met by a counter current of stripping steam, the pressure on the tower being maintained at approximately 50 mm. Hg.

The vapors pass off the stripping tower into the surface condenser 15 at the rate of 750 pounds per hour where they are condensed, the steam passing to the catchall and finally to the barometric condenser. Five hundred pounds of the condensed low boiling fatty acid is returned to the top of the stripping tower as reflux while 250 pounds is removed as product.

Within the stripping tower, the main portion of the feed stock flows downward over several stripping trays, being thoroughly stripped of non-condensable gases and air, moisture, and low boiling impurities.

The dried and de-aerated feed stock flows to the main fractionating tower by gravity through line 18. A pressure of 2 mm. Hg is maintained at the top of the tower while the pressure at the base is not substantially greater than 32 mm. Hg. The temperature at the base of the tower

is maintained at about 482° F. Due to the fact that all of the unsaturated acid is still with the bottoms, the entire bottom mass boils at approximately the same temperature as the pure acid. No steam is required in the fractionating tower.

Six thousand pounds per hour of palmitic acid vapor issues from the top of the fractionating tower and is condensed in the surface condenser 22, 5000 pounds of the condensate being pumped back to the top tray of the fractionating tower as reflux and 1000 pounds being pumped to storage as finished product. The bottoms, which comprise about 70 to 80 per cent of the incoming stock, are drawn into the flash drum or chamber which is maintained at 2 mm. Hg or less, and allowed to vaporize, the latent heat of vaporization being furnished by the sensible heat carried in the stock, no additional heat being required. Twenty-five hundred pounds of the unsaturated acids are removed as vapors in the flash chamber and condensed in the surface condenser 29 from whence it is pumped to storage.

The bottoms from the flash chamber contain considerable quantities of unsaturated acids, the actual percentage being controlled at such an amount as to insure a very pure unsaturated cut; in other words, I avoid getting down too close to the non-volatile matter.

The bottoms (approximately 1500 pounds per hour) are pumped to the top tray of the bottom section of the stripping tower where they are met with a counter-current of super-heated stripping steam which removes the volatile fatty acids and carries them up to the top section of the tower where they are condensed with the feed stock. The non-volatile matter passes downward over the stripping trays and is removed from the base of the tower, the amount of super-heated steam being regulated so as to give the desired stripping results (approximately 400 pounds per hour). This amount can be varied over fairly wide limits as the pressure in the fractionating tower is from 50 to 70 mm. Hg.

It will be noted that in the flow of the feed stock through the stripping tower, fractionating tower, and flash drum, no pumps are employed, the flow being by gravity. Tower nozzles, valves and other fittings are reduced in number and sources of leakage are reduced. The term "gravity" is used in this specification in a broad sense to denote difference of pressure and is not limited to the earth's pull, for obviously a difference of pressures and not the earth's pull is responsible for flow through pipe 28 as shown in the drawing.

With the new method as described, it is possible to obtain an extremely high vacuum at low costs. The flash chamber and the fractionating tower can readily be operated at pressures of 1 to 2 mm. Hg without the compression of steam because no low boiling materials, water, air and non-condensable gases are present, the steam being eliminated from the fractionating tower and the feed stock being de-aerated and dried in the stripping tower.

Relatively low temperatures can be employed by virtue of the removal of the fractions in the stepwise method. The unsaturated fraction is removed by a flash distillation step where no heat is applied during the vaporization stage.

The fatty acid remaining in the bottoms is stripped by means of a high ratio of steam at a point in the system where the steam does not interfere with the high vacuum operation. Efficient

and thorough stripping is accomplished at low temperatures. The stripped fatty acid is returned to the feed stock directly and with no heat loss, the latent heat contained in the acid being utilized for removing the moisture and low boiling material in the feed stock. It will be noted that the unsaturated fraction is heated only in the fractionating tower. Since the moisture is removed from the feed stock, there is no surging within the fractionating tower, as would otherwise be produced through a variation in the moisture content of the stock.

While in the foregoing description of the process, I have set forth certain steps as desirable, it will be understood that a number of such steps may be omitted or carried on in different sequences without departing from the spirit of my invention.

The phrase "fatty acid-containing stock" as used herein and in the claims appended, is intended to include pure fatty acid mixtures and/or stock-containing fatty acids and glycerides, etc.

I wish it to be understood that I do not desire to be limited to the exact details of construction shown and described, for obvious modifications will occur to a person skilled in the art.

I claim:

1. In apparatus of the class set forth, a tube heater through which fresh charging stock may be passed, a stripping and fractionating tower, means for passing the stock from said tube heater into said tower, a second fractionating tower, a flash drum, means for returning bottoms from said flash drum to an intermediate portion of said first tower, means for introducing steam into said first tower, communicating pipes between said first and second tower permitting stock to flow by pressure difference from said first tower into said second tower, and communicating pipes between said second tower and said flash drum permitting stock to flow from said second tower into said flash drum by pressure difference.

2. In apparatus of the class set forth, a tube heater, a first fractionating tower, means for passing stock through said tube heater into the upper portion of said first fractionating tower, a second tower, means for introducing steam into the lower portion of said first tower, means for producing a pressure below atmospheric in the upper portion of said first tower, a flow line permitting flow by pressure difference from a central portion of said first tower into a central portion of said second tower, means for producing a pressure below atmospheric in the upper portion of said second tower, a flash drum, a flow line causing stock to flow by pressure difference from the bottom portion of said second tower into said flash drum, means for producing a pressure below atmospheric in said flash drum, and means for returning stock from the bottom of said flash drum to the lower portion of said first tower.

3. In apparatus of the class set forth, a tube heater, a first fractionating tower, means for passing stock through said tube heater and into the upper portion of said first tower, a second fractionating tower, means for introducing steam into the lower portion of said first tower, a flow line permitting flow by pressure difference of liquid from the central portion of said first tower into said second fractionating tower, said line providing a closed conduit for permitting flow of liquid in a confined stream from said first tower to said second tower, and means for maintaining the second tower under subatmospheric pressure substantially below the pressure in the first tower.

4. In apparatus of the character set forth for treating fatty acid materials, a fractionating tower having an upper section containing rectifying apparatus and a lower section containing stripping apparatus, said rectifying apparatus including a series of rectifying zones through which vaporized fatty acid materials may pass and including also means for passing liquid fatty acids to said zones as reflux liquid, means for withdrawing a low boiling fatty acid from said rectifying section, means for introducing steam into said stripping section, means for withdrawing a bottom material from the lower portion of said stripping section, a second fractionating tower containing a series of rectifying zones, means for introducing reflux liquid to said zones in said second tower, means for withdrawing separately a plurality of fatty acid fractions having different boiling points from said second tower, said towers being connected by a closed conduit permitting flow of liquid from the central portion of said first tower to said second tower and means for maintaining said first tower under a reduced pressure and said second tower under a lower reduced pressure.

5. In apparatus of the character set forth for treating fatty acid materials, a tube heater through which said fatty acid materials may be passed, a fractionating tower having an upper section containing rectifying apparatus and a lower section containing stripping apparatus, said rectifying apparatus including a series of rectifying zones through which vaporized materials may pass and including also means for passing liquid fatty acids to said zones as reflux liquid, means for passing the heated materials from said tube heater into said tower, means for withdrawing a low boiling fatty acid fraction from said rectifying section, means for withdrawing non-volatile material from said stripping section, means for introducing steam into said stripping section, a second fractionating tower containing a series of rectifying zones, means for introducing reflux liquid to said zones in said second tower, means for withdrawing separately a plurality of fatty acid fractions of different boiling points from said second tower, said towers being connected by a closed conduit, permitting flow of liquid in a confined stream from said first tower to said second tower, and means for maintaining said first tower under a reduced pressure and said second tower under a lower reduced pressure.

6. In an apparatus of the character set forth for treating fatty acid materials, a tower containing a series of fractionating zones, means for withdrawing a low boiling fatty acid fraction from an upper portion of said series of zones, means for condensing and returning at least a portion of said withdrawn fraction to said upper portion as reflux liquid, a stripping tower for receiving fatty acid feed stock, means for introducing steam into said stripping tower to strip the feed stock therein, means for passing a confined stream of liquid from said stripping tower to said fractionating tower, means for maintaining said fractionating tower under subatmospheric pressure substantially below the pressure in said stripping tower, means for withdrawing a high boiling fraction containing non-volatile material from a lower portion of said fractionating tower, and means for passing at least a part of said withdrawn fraction to said stripping tower.

7. In apparatus of the character set forth for treating fatty acid materials, a tower containing a series of fractionating zones, means for withdraw-

ing a low boiling vaporous fatty acid fraction from an upper portion of said tower, means for condensing and returning at least a portion of said withdrawn fraction to the upper portion of said tower as reflux liquid, a stripping tower for receiving fatty acid feed stock, means for introducing steam into said stripping tower to strip the feed stock therein, said towers being connected by a closed conduit permitting flow of liquid in a confined stream from said stripping tower to said fractionating tower, said conduit being equipped with means for preventing flow of steam with said liquid through the conduit, means for maintaining said fractionating tower under atmospheric pressure substantially below the pressure in said stripping tower whereby the fractionating tower may be maintained substantially free of gases and vapors foreign to said fatty acid materials, means for withdrawing a high boiling fraction containing non-volatile material from a lower portion of said fractionating tower, means for distilling volatile material from said fraction withdrawn, means for maintaining said distilling means under a subatmospheric pressure lower than the pressure in the lower portion of said fractionating tower, and means for passing non-volatile matter from said distilling means to said stripping tower.

8. In apparatus of the character set forth for treating fatty acid materials, a tower containing a series of fractionating zones, means for withdrawing a low boiling fatty acid fraction from an upper portion of said tower, means for condensing and returning at least a portion of said withdrawn fraction to the upper portion of said tower as reflux liquid, a stripping tower, means for introducing steam into said stripping tower, means for maintaining said fractionating tower under subatmospheric pressure substantially lower than the pressure in said stripping tower, said fractionating tower being substantially free of gases foreign to said fatty acid materials, means for withdrawing a high boiling fraction containing non-volatile material from a lower portion of said fractionating tower, means for passing at least a part of said withdrawn high boiling fraction to said stripping tower, and conduit means connecting said stripping tower to said fractionating tower whereby liquid acids stripped from said non-volatile material may pass again to said fractionating tower, said conduit means being equipped with a trap for preventing flow of steam with said liquid acids through said conduit means.

9. In apparatus for treating fatty acid materials, a stripping and fractionating tower, means for passing the fatty acid material stock into said tower, a second fractionating tower, a flash drum, means for returning stock from said flash drum to an intermediate portion of said first tower, means for introducing steam into said first tower, communicating conduits between said first and second towers permitting said stock to flow from said first tower into said second tower, and communicating conduits between said second tower

and said flash drum permitting stock to flow from said second tower into said flash drum.

10. In apparatus for treating fatty acid materials, a first fractionating tower, means for passing fatty acid material stock into said fractionating tower, means for introducing steam into said tower, means for producing a pressure below atmospheric in the upper portion of said tower, a second fractionating tower, a flow line permitting flow of liquid from said first tower to said second tower, means for producing a subatmospheric pressure in the upper portion of the second tower lower than the pressure in the upper portion of the first tower, a flash drum, a flow line for permitting liquid to flow from the lower portion of said second tower into said flash drum, means for producing a subatmospheric pressure in said flash drum below the pressure in the lower portion of said second tower, and means for returning stock from the bottom of said flash drum to the lower portion of said first tower.

11. In apparatus for the separation of a mixture containing fatty acids of different boiling points, a fractionating tower equipped with means for supporting a series of spaced pools of fatty acid within said tower, means for introducing fatty acid stock into said tower, an outlet in said tower for withdrawing lower boiling vaporized fatty acid from above the upper of said pool-supporting means, means for maintaining in said tower about the upper of said pool-supporting means a high vacuum which extends to a lesser degree about the lower of said pool-supporting means, means for introducing steam into said tower, a flash drum providing a distillation chamber, means including a conduit for passing liquid higher boiling fatty acid from the lower of said pool-supporting means to said flash drum, means for maintaining a high vacuum in said distillation chamber which vacuum is higher than the vacuum about the lower of said pool-supporting means in said tower, an outlet for withdrawing vaporized higher boiling fatty acid from said drum, and an outlet for withdrawing unvaporized residue from said drum.
